UNITED STATES PATENT OFFICE.

CHARLES C. TRAPP, OF PORT WASHINGTON, WISCONSIN.

REVOLVING CHAIR.

SPECIFICATION forming part of Letters Patent No. 424,083, dated March 25, 1890.

Application filed August 3, 1889. Serial No. 319,623. (No model.)

To all whom it may concern:

Be it known that I, CHARLES C. TRAPP, of Port Washington, in the county of Ozaukee and State of Wisconsin, have invented new and useful Improvements in Revolving Chairs; and I do hereby declare the following to be a full, clear, and exact description of said invention, reference being had to the accompanying drawings, and to the letters of reference 5 marked thereon, which form a part of this specification.

It is common to support the revolving seat of a chair by a spindle with a screw-thread turning in a head fixed on the legs of a chair, 15 by which device the seat of the chair may be rotated while the legs remain stationary, at the same time raising and lowering the seat with reference to the legs by reason of the screw-thread on the spindle.

20 My invention is of a device whereby the seat of a chair is permitted to revolve without raising or lowering it with reference to the legs, the adjustment up and down being secured by independent mechanism.

25 In the drawings, Figure 1 is an elevation of my improved device. Fig. 2 is a central vertical section of the same device. Fig. 3 is a transverse section on line 3 3 of Fig. 2.

A is a metal head, provided with sockets B 30 B, adapted to receive therein the upper extremities of the legs C, on which it is permanently supported rigidly. The metal head A is provided with a central vertical aperture, in which the cylindrical spindle D is fitted 35 and moves freely. A bracket E, adapted to support the chair-seat thereon, is fixed rigidly on the top of the spindle D, being conveniently secured thereto by means of the screw F, though any other equivalent means of securing the bracket to the spindle could be 40 used. An arm G has an aperture at one end, through which shank N of the spindle D passes and in which it rotates freely, and at the other end the arm G carries rigidly affixed thereto at right angles a screw H, which projects through sockets therefor in the side of the head A, and is provided with a milled nut I, turning thereon in a recess therefor in the side of the head A, which nut bears at its upper 45 and lower ends against the walls of said recess. A set of friction-wheels K K K are preferably

used, having their journals in bearings therefor in downwardly-projecting flanges L L, rigid on the bracket E, which travel on the arm G and support the bracket and its load 55 thereupon.

The spindle D is preferably provided with a shoulder M, the part above the shoulder forming a shank N of somewhat smaller diameter than the main part of the spindle, 60 which shank only enters the aperture in the arm G, whereby the spindle has but slight endwise movement in the arm G, and may not be withdrawn therefrom without releasing the bracket E from the spindle. One or 65 more pins O inserted in the spindle D would support the arm G successfully, and the shoulder M could be omitted.

It will be understood that the seat which is supported on the bracket E may be rotated horizontally with the spindle D, and that the seat will not be raised or lowered by such rotation, but that the seat supported on the bracket E is supported and travels around (on the friction-wheels K K) on the arm G, 70 and that the seat is elevated or lowered by turning the nut I on the screw H, whereby the screw H is raised or lowered vertically in the head A, thereby carrying the bracket E, with its superimposed structure, up or down, 75 80 as desired.

What I claim as new, and desire to secure by Letters Patent, is—

1. The combination, with the metal head supported on the legs of a chair and a spindle 85 rotating therein, which spindle is adapted to be secured to the seat of a chair, of a screw provided with an arm, through which the spindle is passed loosely, which screw passes through sockets therefor in the metal head, 90 and a nut turning on the screw and bearing at its ends against the metal head, substantially as described.

2. In a device for supporting the seat of a chair, a spindle carrying the chair-seat fixedly thereon, which spindle is rotatable in a supporting-head, in combination with the supporting-head, a screw located alongside the spindle, which is movable endwise but not rotatable in the supporting-head, a nut turning 95 on the screw and having bearings at both ends against the supporting-head, and an arm 100

fixed to the screw, through which arm the spindle passes and on which it is supported, substantially as described.

3. In a device for supporting the revolving seat of a chair, the combination, with a bracket E and a spindle D affixed thereto, of friction-wheels K K, journaled in the bracket E, and an arm G, on which the friction-wheels travel, affixed to and supported on a screw H, adjustable vertically in a fixed support, substantially as described.
4. The combination, with a bracket E, pro-

vided with friction-wheels K K and a spindle D, of a head A, a therein-guided screw H, provided with a rigid arm G, and a nut I, turning on the screw H and bearing against the head A, substantially as described. 15

In testimony whereof I affix my signature in presence of two witnesses.

CHARLES C. TRAPP.
